Inventor:

Robert M. Cox
By his Atty. # UNITED STATES PATENT OFFICE.

ROBERT M. COX, OF PHILADELPHIA, PENNSYLVANIA.

DESIGN FOR A PRISM-PLATE.

SPECIFICATION forming part of Design No. 32,550, dated April 17, 1900.

Application filed March 7, 1900. Serial No. 7,743. Term of patent 14 years.

To all whom it may concern:

Be it known that I, ROBERT M. COX, of the city and county of Philadelphia, in the State of Pennsylvania, have invented a new and original Design for Prism-Plates, of which the following is a specification.

My new and original design for a prism-plate is shown in the accompanying drawings, in which—

Figure 1 is a perspective view of a prism-plate embodying my design. Fig. 2 is a vertical sectional view on the line 2 2 of Fig. 1, and Fig. 3 is a transverse sectional view on the line 3 3 of Fig. 1.

The design resides in the surface shape or configuration of the faces of a sheet or plate of glass.

One face of the plate is formed of a series of small prismatic ribs *a* and the other of a series of parallel concave depressions *b*, extending transversely to the small prismatic ribs *a*.

What I claim as new, and desire to secure by Letters Patent, is as follows:

The design for a prism-plate substantially as described and as shown in the accompanying drawings.

In testimony of which invention I have herenunto set my hand.

ROBT. M. COX.
